UNITED STATES PATENT OFFICE

131,385

DESIGN FOR A BATHING CAP

Barbara Field Crohn, New York, N. Y.

Application January 23, 1940, Serial No. 89,647

Term of patent 3½ years

To all whom it may concern:

Be it known that I, Barbara Field Crohn, a citizen of the United States and a resident of the city of New York, in the county of New York and State of New York, have invented a new, original, and ornamental Design for a Bathing Cap, of which the following is a specification, reference being had to the accompanying drawing, constituting a part thereof in which

Fig. 1 is a bottom plan view of a bathing cap showing my new design.

Fig. 2 is a side elevational view of the same.

The characteristic feature of my design resides in the combination, in the bathing cap disclosed, of a tight fitting front portion in association with a snood-like rear portion, said rear portion having a fullness on the underside thereof adjacent the band, said bathing cap being symmetrical on each of its two sides, all as shown.

I claim:

The ornamental design for a bathing cap, as shown and described.

BARBARA FIELD CROHN.
